VENETIAN BLIND RESTRINGER

Clarence Nokes, Washington, D. C.

Application May 28, 1956, Serial No. 587,891

1 Claim. (Cl. 29—241)

The present invention relates to Venetian blind restringers, and more particularly to a device for assisting in the replacing of the lifting cord of a Venetian blind.

The primary object of the invention is to provide a restringing device which is adapted to be utilized for replacing worn or broken Venetian blind lifting cords without requiring the disassembly of the blind.

Another object of the invention is to provide a restringing device of the class described above which is adapted to cooperate with the worn or broken Venetian blind cord so as to be guided thereby into restringing position.

A further object of the invention is to provide a Venetian blind restringing device of the class described above which is inexpensive to manufacture, simple to operate and use, and completely effective in its action.

Other objects and advantages will become apparent in the following specification when considered in the light of the attached drawings, in which:

Figure 1 is a side elevation of the invention.

Figure 2 is a longitudinal cross-section taken along the line 2—2 of Figure 1, looking in the direction of the arrows.

Figure 3 is a transverse cross-section taken along the line 3—3 of Figure 1, looking in the direction of the arrows.

Figure 4 is an enlarged fragmentary detail cross-section taken along the line 4—4 of Figure 1, looking in the direction of the arrows.

Figure 5 is a side elevation of a modified form of restringing device.

Figure 6 is a diagrammatic view of the cords of a Venetian blind to be replaced by using the invention.

Referring now to the drawings in detail wherein like reference characters indicate like parts throughout the several figures, the reference numerical 10 indicates generally a Venetian blind cord which is adapted to be trained over pulleys 11 and 12 and double pulley 13 shown diagrammatically in Figure 6 to provide a pair of lifting lengths 14 and 15.

Dependent portions 16 and 17 extend downwardly from the pulley 13 and integrally join respectively to the lengths 14 and 15. The dependent portions 16 and 17 are integrally joined at 18 to form a loop. The lengths 14 and 15 have terminal ends 19 and 20, respectively thereon, for engagement with the lower bar of a Venetian blind structure (not shown).

A restringer for replacement of the cord 10 is generally indicated at 21 and consists of a body 22 formed of relatively soft flexible material, such as rubber or the like, having a tapered end portion 23 and a cylindrical body portion 24 integrally joined to the tapered end portion 23 and extending axially therefrom.

The cylindrical portion 24 is provided with a bore 25 extending from the end 26 opposite the tapered end portion 23 completely through the cylindrical portion 24 to the tapered end portion 23. The cylindrical portion 24 is provided with an open side 27 extending from a point

2

spaced from the end 28 of the bore 25 to a point 29 spaced inwardly from the end 26 of the cylindrical body 24.

A pair of sharpened pins 30 are provided with heads 31 on one end thereof which are molded into the cylindrical portion 24 with the sharpened points 32 thereof extending into the bore 25 in the cylindrical portion 24. The pins 30 are angled in a direction toward the tapered end 23, as best illustrated in Figure 3.

A short length of ball chain 33 has a portion 34 thereof molded into the tapered end portion 23 of the restringer 21. The chain 33 is provided with an outer terminal ball 35. A length of chain 36 is provided for attachment to the restringer 21 by means of a chain connector 37 of conventional construction. A T-head handle 38 is provided with a chain ball 39 at the terminal end of its shank and is adapted to be connected to the chain 36 by means of a chain connector 40.

Referring to Figure 5, there is illustrated a modified form, indicated generally at 21', of the restringer 21. The modified restringer 21' is provided with a flexible body 22' having a tapered end portion 23' and an integral cylindrical body portion 24' extending longitudinally of the tapered end portion 23'. A short length of ball chain 41 is embedded in the end 26' of the cylindrical body 24', for reasons to be assigned.

In the use and operation of the invention, when the Venetian blind cord 10 becomes worn and frayed, it is imperative that it be replaced to permit the normal operation of the Venetian blind since continued use of such a cord will result in its breaking, rendering the Venetian blind inoperative.

When it is desired to replace the cord 10, the loop 18 connecting the portions 16 and 17 is cut, and the cut end 35 of the portion 16 is inserted into the bore 25 of the restringer 21. A length of chain 36 is connected to the chain 33 by means of the connector 37, and the length 14 of the cord 10 is pulled pulling the portion 16 under the pulleys 13 and 11 until the restringer 21 reaches a point generally indicated at 42 lying between the pulleys 11 and 12. With the parts in this position, the chain 36 replaces the portion 16 of the cord 10 and is trained over the pulley 13.

A second restringer 21 is then connected to the cut end of the portion 17 by inserting it in the bore 25 of the restringer 21. A third restringer 21 is connected to a length of new replacement cord (not shown) and this restringer 21 is connected to the restringer 21 on the cut end of the portion 17 by means of their respective short chains 33 and a connector 37. As can readily be seen this arrangement provides a positive connection between the cut end of the portion 17 and one end of the new replacement cord. The length 15 of the cord 10 is then pulled, moving the portion 17 about the pulleys 13 and 12.

55 The connectors 21 are permitted to pass over the pulley 13 due to the small size of the chain 36 lying thereon in place of the length 16 of the cord 10. The length 15 and the portion 17 of the cord 10 are pulled until the new cord extends to the terminal point 20 whereupon the restringers 21 are disconnected therefrom and from the old cord 10. One of the restringers 21 is then secured to the end of the new cord opposite to that trained over the pulleys 12 and 13 by having the end of the new cord inserted in the bore 25.

60 The short chain 33 of the restringer 21 is then connected to the chain 36 which is replacing the portion 16 by means of a connector 37. The old cord 10 connected to the chain 36 is then pulled about the pulley 11 until all of the chain 36 and the new cord are trained over the pulleys 13 and 11 and the new cord reaches the terminal end 19. This completes the restringing and the new

cord is then connected to the bottom bar of the Venetian blind in the usual manner. It should be understood that while I have described one method of restringing Venetian blinds, the restringer 21 is adapted for other methods of restringing.

The restringer 21' illustrated in Figure 5 is used for restringing operations when the cord 10 is broken or completely missing. The restringer 21' is used similar to a needle passing through the holes in the Venetian blind slats pulling the short chain 41 therethrough. In stringing a blind with the restringer 21' a new cord can be connected thereto through a restringer 21 and connector 37, or it can be first utilized to thread a chain 36 through the Venetian blind so that it can then be used to pull a new cord therethrough.

The T-handle 38 is adapted to be used with any of the chains 36 to pull the chain 36 through a Venetian blind after the removal of the restringer 21.

Having thus described the preferred embodiments of the invention, it should be understood that numerous other structural modifications and adaptations may be resorted to without departing from the scope of the appended claim.

What is claimed is:

A Venetian blind restringing device comprising an

elongated flexible elastic molded cylindrical body, a solid tapered end portion integrally formed on one end of said body, said body having an axial bore extending inwardly thereof from the end opposite said tapered end portion, said cylindrical body having an opening through the side thereof communicating with said bore, a relatively short length of ball chain having an end portion thereof molded into the tapered end portion of said body for connecting said body to an operator, and a pair of sharpened pins molded into the wall of said bore and extending at an angle into said bore toward said tapered end portion for engaging and securing a Venetian blind cord therein, said sharpened pins being molded into the wall of said bore on the side thereof opposite the opening in said cylindrical body communicating with said bore in aligned relation thereto.
